LOOM ATTACHMENT

Berry W. Green and Hubert L. Nalley, Easley, S. C.

Application May 11, 1940, Serial No. 334,542

3 Claims. (Cl. 139—336)

This invention relates to a loom attachment and more especially to a compression brake spring which serves to apply brakes when the shipper lever is actuated to stop the loom.

5 Heretofore, much difficulty has been experienced with conventional tension springs commonly used for this purpose, in that the springs often crystallize and break, thus necessitating replacement. Also the tension springs often lose 10 some of their resiliency after continued use, with the result that adjustment is necessary in order to produce the desired uniform tension.

It is an object of this invention to provide a compression spring for applying loom brakes 15 which spring is normally in a compressed position during the operation of the loom, and which is in an expanded position when the loom is stopped and the brakes are applied.

It is another object of this invention to provide 20 a spring of the class described, with means for adjusting the amount of compression or resistance that the spring offers, when in a compressed position. By providing this adjustment an ample allowance for the fatigue in the spring can be made from time to time, thereby maintaining a substantially constant force stored in 25 the spring when it is compressed.

Another object of this invention is to provide a compression spring which encircles a rod and 30 which has one end thereof normally forcing the rod against the brake applying mechanism. The other end of the spring abuts a stationary member attached to the loom, said stationary member being slidably penetrated by the other end of the rod. The rod, therefore holds the spring in 35 the proper position and also serves to apply the brakes when it is released by the action of the shipper lever.

Some of the objects of the invention having 40 been stated, other objects will appear as the description proceeds, when taken in connection with the accompanying drawings, in which—

Figure 1 is a side elevation of a loom showing the improved attachment applied thereto;

Figure 2 is an elevation looking at the right hand side of Figure 1;

Figure 3 is a sectional plan view taken along the line 3—3 of Figure 2;

Figure 4 is an isometric view showing the loom attachment removed from the loom;

Figure 5 is a view similar to the left-hand portion of Figure 2, but showing a slightly modified form of the invention.

Referring more specifically to the drawings, the 55 numeral 10 denotes a side frame of a loom upon which is mounted a warp beam 11 from which warp 12 is drawn. This warp passes upwardly over a roller 14 and thence across the loom beneath rod 15 at which point it is separated into sheds 16 and 17. The shed 16 is actuated by

suitable heddles 18 whereas the shed 17 is actuated by similar heddles 19. The warp passes through reed 20 in a conventional lay 21. Upon the lay a shuttle, not shown, is adapted to reciprocate back and forth between the sheds to 5 form cloth 22 in a conventional manner.

The lower portion of the lay 21 has a dagger 25 pivoted thereto and this dagger is adapted to be maintained in an elevated position as shown in Figure 1, when the same is disposed over frog 10 steel 26 in frog 27. Frog 27 is slidably mounted upon the loom frame 10, but it is not disturbed unless some faulty operation of the loom allows the free end of the dagger 25 to be in a lowermost position to engage the same during the 15 beat-up stroke of the loom lay.

The frog 27 has secured thereto as at 30, a plate member 31, one end of said member being adapted to be engaged by the lower end of a knock-off lever 32 which lever is pivoted as at 20 33 to the side of the loom frame. The upper end of the knock-off lever engages the side of shipper lever 34, said shipper lever being adapted to penetrate a slot 35 in casting 36, which casting is secured to the loom frame. The intermediate portion of the shipper lever 34 is pivoted as at 37 to a bracket 38 and this bracket is also secured to the loom frame.

During normal operation, that is when cloth is being woven, the shipper lever 34 is adapted 30 to rest in a notch 35a which is formed in the sidewall of the slot 35. Upon the shuttle becoming absent in the shuttle box during the beat-up stroke of the loom lay, the free end of dagger 25 will not be raised to the position shown in Figure 1, but will be moved from left to right in a lowered position thereby causing its free end to engage the frog steel 26. This engagement will cause the frog 27 and its associated plate 31 to also move to the right to cause the knock-off 40 lever 32 to be rotated in a counter-clockwise manner in Figure 1. This rotation of the knock-off lever will move the upper end of the shipper lever 34 out of the notch 35a after which the lever will assume the dotted line position as shown in 45 Figures 2 and 3.

The shipper lever 34 has a projection 40 integral therewith, said projection being adapted to support the free end of a lever 41. Lever 41 is a part of the brake applying mechanism and is 50 pivoted as at 42 to the side of the loom frame 10, said lever having an upwardly extending projection 43 integral therewith which is adapted to contact a bracket 44 on horizontally disposed rod 45. The right hand end of the rod 45 (Figure 1) has a slot 46 therein, which slot is penetrated by a bolt or screw 47. This screw 47 secures the right hand end of the rod 35 to the frog 27. The purpose of providing the slot 46 is to allow a limited amount of horizontal move- 60

ment of the rod 45 without affecting the movement of the frog. The left-hand end of the rod 45 is pivoted as at 45a to the upper portion of brake lever 48, said lever having its lower end 5 pivoted as at 49 to the loom frame.

The upper portion of the brake lever 48 has a brake lining 50 secured to one side thereof which normally is slightly removed from the periphery of wheel 51 on crank shaft 52. Upon the release 10 of the shipper lever 35 in the manner just described, causing it to assume dotted line position in Figures 2 and 3, the lever 41 is likewise released and allowed to rotate downwardly in a clockwise manner about its pivot point 42. The 15 rotation of the lever 41 and projection 43 in a clockwise manner, will simultaneously cause the bracket 44 and the rod 45 to move to the right which in turn will cause the upper end of the brake lever 48 to move the lining 50 into engagement 20 with the periphery of the wheel 51 to apply brakes.

The structure thus far described is conventional in loom structure, but it is thought necessary to describe this much of the old structure 25 in order to more clearly illustrate the present invention. The present invention comprises a compression spring assembly for causing the free end of lever 41 to follow the projection 40 downwardly when the shipper lever 34 is unlatched. 30 By referring to Figures 2 and 3, it will be seen that the bracket 36 has a projection 55 extending therefrom and this projection has a horizontally disposed slot 56 therein. The slot 56 is penetrated by a suitable bolt 57, said bolt also penetrating a hole 58 in the upper end of a bracket or fitting 59. A vertically disposed hole is provided in the bracket 59 for slidably confining the upper end of a rod 60 therein, said rod 60 extending downwardly and having a forked portion 61 integral with the lower end thereof for resting upon the upper side of the free end of lever 41. Also secured around the rod 60 and directly above the forked portion 61 is a collar 63. This collar is adjustably secured in position 45 by means of a suitable set screw 64. Between the bracket or fitting 59 and the upper side of the collar 63 a compression spring 65 is mounted around the rod 60. When the shipper lever 34 is released the spring 65 normally forces the collar 63 and the rod 60 downwardly to face the fork 61 against the free end of the lever 41 thereby causing the lever to rotate in a clockwise manner about pivot point 42 (Figure 1), which, in turn, will move the rod 45 and the upper end 55 of brake lever 48 to the right to apply brakes to the wheel 51.

When it is desired to adjust the amount of compression offered by the spring 65, it is only necessary to loosen the set screw 64 and reposition the collar 63 on the shaft 60.

Figure 5 shows a slightly modified form of the invention in which the compression brake spring assembly comprises a bracket 70 having a vertically disposed slot 71 in the upper end thereof, 65 said slot being penetrated by bolt 72 to secure the same to portion 55. The bracket also has the upper end of a rod 73 slidably mounted therein and the lower end of this rod has a fork 74 disposed on the upper side of lever 41. A collar 70 75 is integrally formed on the lower portion of rod 73 for supporting the lower end of a compression spring 76, which spring is disposed around the intermediate portion of the rod and has its upper end engaging bracket 70. In order 75 to adjust the initial resistance offered by the

spring, the bolt 72 must be loosened so that the bracket can be moved up or down to the position desired.

It is therefore seen that we have provided a simple and inexpensive apparatus for supplying the necessary force to the brake mechanism of a loom. This mechanism is simple in operation, 5 low in cost, easy to manufacture and has many advantages over the present type of tension spring employed for this same purpose. 10

In the drawings and specification, there has been set forth a preferred embodiment of the invention, and although specific terms are employed they are used in a generic and descriptive sense only and not for purposes of limitation the 15 scope of the invention being set forth in the appended claims.

We claim:

1. In a loom having a brake mechanism and a shipper lever having a projection thereon disposed in the path of the brake mechanism when the shipper lever is in latched position for preventing operation of the brake mechanism while the loom is in operation, means for holding the brake mechanism in engagement with the projection on the shipper lever comprising a stationary fitting secured to the loom frame, a rod having one end thereof slidably mounted in said fitting, and having a fork on its other end engaging the brake mechanism, and a compression 20 spring disposed around the rod and normally forcing the same against said brake mechanism, whereby the shipper lever will be moved and the brake mechanism will be applied by the spring when the shipper lever is unlatched. 25

2. In a loom having a brake mechanism and a shipper lever having a projection thereon disposed in the path of the brake mechanism when the shipper lever is in latched position for preventing actuation of the brake mechanism while the loom is in operation, means for holding the brake mechanism in engagement with the projection on the shipper lever comprising a stationary fitting secured to the loom frame, a rod having one end thereof slidably mounted in said fitting, 40 and having its other end engaging the brake mechanism, a compression spring disposed around the rod and normally forcing the same against said brake mechanism whereby the shipper lever will be moved and the brake mechanism will be applied by the spring when the shipper lever is unlatched, and means for varying the amount of resistance offered by the spring. 45

3. In a loom having a brake mechanism and a shipper lever having a projection thereon disposed in the path of the brake mechanism when the shipper lever is in latched position for holding the brake mechanism in inoperative position while the loom is in operation, means for holding the brake mechanism in engagement with the projection on the shipper lever comprising a stationary fitting secured to the loom frame, a rod having a collar adjustably mounted thereon, one end of said rod being slidably mounted in said fitting and its other end being engaged by the 55 brake mechanism, a compression spring disposed around the rod between the collar and the fitting for normally forcing the lower end of the rod in engagement with the shipper lever, whereby the shipper lever will be moved and the brake mechanism will be applied by the spring when the shipper lever is unlatched. 60
